UNITED STATES PATENT OFFICE.

WILLARD E. CLEVELAND, OF OREGON, ILLINOIS, ASSIGNOR TO NATIONAL PIANO PLAYER COMPANY, OF OREGON, ILLINOIS, A CORPORATION OF ILLINOIS.

COIN-EJECTOR FOR MUSICAL INSTRUMENTS.

No. 910,502.

Specification of Letters Patent.

Patented Jan. 26, 1909.

Application filed August 26, 1907. Serial No. 390,155.

To all whom it may concern:

Be it known that I, WILLARD E. CLEVELAND, a citizen of the United States, residing at Oregon, in the county of Ogle and State of Illinois, have invented certain new and useful Improvements in Coin-Ejectors for Musical Instruments, of which the following is a specification.

The object of this invention is to positively 10 eject a coin thereby stopping the action of the instrument.

In the accompanying drawings, Figure 1 is a face representation of a portion of the frame of a musical instrument to which I 15 have applied my improvements. Fig. 2 is a vertical section through the casing for the operative parts, in which the top plate of insulating material is removed, and in which the coin is shown in operative position. 20 Fig. 3 is a similar section in which the coin is to be forcibly ejected. Fig. 4 is a transverse section on dotted line *a—a* Fig. 2.

The frame 1 of the musical instrument is formed with a coin chute 2. A casing is 25 secured to the frame and comprises the back 3, edges 4, top 5 and front 6.

To the back 3 of the frame is secured a plate 7 of insulating material, and some distance from this plate 7 is located a support 30 8 of insulating material to which are connected two binding posts 9 and 10, the screw sections of which rest in contact with the plate 7 of insulating material in order that they may be insulated from the casing. 35 From the face of this support 8 of insulating material project two sections 11 and 12 over which is located a face plate 13 of insulating material and held in contact therewith by the nuts 14 applied to the binding posts 9 40 and 10.

To the face of the support 8 are secured two metallic plates 15 and 16 held separated some distance. The plate 15 has an out-turned edge 17. A wire 18 connects the 45 plate 15 with the binding post 10, and a wire 19 connects the plate 16 with the binding post 9.

To the support 8 of insulating material is pivoted a coin ejector comprising the coin 50 rest 20, ejecting finger 21, weighted tail section 22 and tripping extension 23.

To the casing is secured a pneumatic 24,

and to the movable section 25 of this pneumatic is secured an arm 26.

A tube 27 is intended to connect the pneumatic with a valve chamber of a musical instrument, the valve in the chamber controlled by a note sheet passing over a tracker-bar in the well known manner. An exhaust pump is intended to connect with the valve chamber in order that the air may be exhausted from the pneumatic. 55 60

The weighted tail section 22 holds the coin ejector in the position shown in Fig. 2, so that the ejecting finger will rest against the 65 adjusting screw 28. The wires 29 and 30 connect the binding posts 9 and 10 with the electric motor.

When a coin 31 is placed in the coin chute 2 it will descend between the support 8 and 70 face plate 13 and will be supported by the coin rest 20 and outturned edge 17 of the metallic plate 15, and will also rest against the metallic plate 16. The coin will form an electrical connection between the plates 15 75 and 16 thereby starting the electric motor, which will set the operative parts in motion to render the music.

After the note sheet has moved on the tracker-bar until the piece of music is finished, an opening in the note sheet will coincide with an opening in the tracker-bar, which will open the valve in the valve chamber and permit the pump to exhaust the air from the pneumatic 24 which action will 80 85 move the arm 26 against the tripping section 23 of the coin ejector, thereby moving the coin ejector on its pivot and cause the ejecting finger 21 to force the coin down and permit it to drop into the coin receptacle 32. The 90 motor will immediately stop, and stop the operation of the instrument. The weighted tail section 22 will return the coin ejector to its normal position. The adjusting screw 28 is used to properly locate the coin ejector so 95 that a coin will pass the ejecting finger 21 and stop on the rest 20.

The weighted tail section 22 will return the movable section 25 of the pneumatic 24 into its normal or expanded position. 100

I claim as my invention.

1. The combination of separated plates with which a coin may contact, an ejector comprising a pivoted rest for a coin, an eject-

ing finger located above the rest, a weighted tail section, and means for moving the ejector thereby causing the rest to release the coin and bring the ejecting finger over the coin to force it down.

2. The combination of separated plates with which a coin may contact, an ejector comprising a pivoted rest for a coin, an ejecting finger located above the rest, a weighted tail section, and pneumatic devices for mov-

ing the ejector thereby causing the rest to release the coin and bring the ejecting finger over the coin to force it down.

In testimony whereof I have hereunto set my hand in presence of two subscribing witnesses.

WILLARD E. CLEVELAND.
